UNITED STATES PATENT OFFICE.

STEPHEN BOURNE, OF NEW YORK, N. Y., ASSIGNOR TO BRANDES LABORATORIES INC.,
OF NEWARK, NEW JERSEY, A CORPORATION OF NEW JERSEY.

DESIGN FOR A BASE FOR A LOUD SPEAKER FOR RADIOPRODUCERS.

Application filed July 27, 1925. Serial No. 14,234. Term of patent 14 years.

To all whom it may concern:

Be it known that I, STEPHEN BOURNE, a citizen of the United States, residing at New York, in the county and State of New York, have invented a new, original, and ornamental Design for a Base for a Loud Speaker for Radioproducers, of which the following is a specification, reference being had to the accompanying drawing, forming part thereof.

Figure 1 is a perspective view of the ornamental base for a loud speaker and Figure 2 is a plan view of the loud speaker base showing my new design.

I claim:

The ornamental design for a base for a loud speaker for radioproducers as shown.

STEPHEN BOURNE.
